UNITED STATES PATENT OFFICE.

GEORGE H. GILMAN, OF BELMONT, MASSACHUSETTS.

DRILLING MACHINE.

Application filed August 22, 1923. Serial No. 658,825.

My invention relates to drilling machines and more particularly to a mounting for a percussive tool.

My invention will be best understood from the following description when read in the light of the accompanying drawings of one specific embodiment of my invention selected for illustrative purposes, while the scope of my invention will be more particularly pointed out in the appended claims.

In the drawings:—

Fig. 1 is a plan view of a drilling machine constructed according to my invention;

15 Fig. 2 is an elevation according to Fig. 1; Fig. 3 is a view of the rearward end of the percussive tool when removed from the mounting and arranged for manual support;

20 Fig. 4 is a section on the line 4—4 of Fig. 2;

Fig. 5 is a plan view of the cradle with parts omitted;

25 Fig. 6 is a longitudinal section of the cradle; and

Fig. 7 is a section on the line 7—7 of Fig. 6.

Referring to the drawings and to the preferred embodiment of my invention I have shown a percussive tool of the hammer type, the casing of which comprises the rearward section 1, the forward section 3, and the intermediate sections 5 and 7, these sections being held in assembled relation by means 30 of a pair of side bolts 9. As shown the rearward section 1 is provided with a reduced portion 11 and at its rearward end with a boss 13 which is laterally extended to form the laterally projecting lugs 15. Referring 35 particularly to Figs. 2 and 3 I have shown the boss with its lugs provided with a perforation 17 through which I place a bolt 19 carrying the handles 21 for adapting the percussive tool for use as a hand tool.

40 45 Forwardly of the reduced portion 13 of the rearward section 1 of the percussive tool is a shoulder 23 serving as an abutment for the rearward heads of the side bolts 9. The intermediate portion of the forward section 50 55 3 of the casing of the percussive tool is reduced at 25 which forms shoulders 27. For adapting the percussive tool to the mounting, against the shoulders 27 I place the ends of a U-shaped member or adapter plate 29, these ends being perforated to receive the side bolts which when tightened

hold the adapter plate rigidly to the percussive tool. At its lowermost portion the forward face of the adapter plate is provided with a forwardly directed lug 31. 60

The mounting for the percussive tool comprises a shell 33 having a trunnion support 35 and a cradle 37. At opposite sides the shell is provided with portions 39 having the longitudinally arranged slots 41 in which 65 the guide bars 43 of the cradle slide. At its forward end the cradle is provided with an upstanding lug 47, the upper portion of which conforms to the surface of the forward section 3 of the percussive tool so as 70 to support it, and is further provided with a perforation 51 which receives the forwardly directed lug 41 of the adapter plate carried by the percussive tool.

75 The rearward portions of the side bars of the cradle are provided with upstanding lugs 53 which embrace the reduced portion 11 of the rearward section of the percussive tool, the lugs 53 having the recesses 55 into which the lugs 15 fit when the lug 31 on the 80 adapter plate is inserted into the perforation 51 of the lug 47 at the front end of the cradle.

At its rearward end the cradle is provided 85 with a boss 57 which is provided with a screw threaded perforation receiving the bolt 59. At its forward end the bolt 59 carries a yoke 61, the ends 63 of which bear against the rearward side of the lugs 15. It will be noted by this construction that the 90 lugs 53 and yokes 61 form the jaws of a vise of which the lugs 53 are the fixed jaw and the yoke 61 the movable jaw. For adapting the yoke 61 to irregularities and 95 discrepancies in the percussive tools employed I have shown the rearward face of the yoke 61 provided with the spherical socket 65 which receives the spherical head 67 of the bolt. Surrounding the rearward end of the bolt is a compression spring 69 100 one end of which fits into a notch 71 on the rearward face of the boss 57, while its rearward end engages ratchet teeth 73 formed on the forward face of the head 75 of the bolt 59. By this means when the vise is 105 closed to clamp the lugs 15 between the jaws of the vise the spring 69 will prevent loosening of the vise under the influence of vibration of the machine.

110 For feeding the cradle relative to the shell the shell is provided with a pair of rearwardly extending arms 77, the rearward

ends of which carry a cross bar 79 which in a manner well understood by those skilled in the art forms a thrust bearing for the feed screw 81. I have indicated the feed 5 screw nut which cooperates with the feed screw in Fig. 6 at 83, the head 85 of the nut having the flattened sides 87 which bear against finished surfaces 89 on the inner sides of the guide bars 43 of the cradle. The 10 feed screw nut is received by a boss 91 on the lowermost portion of the rearward end of the cradle, the projecting rearward portion of the feed screw nut being screw threaded and receiving the nut 93 which 15 holds it in position.

Although I have described for purposes of illustration one specific form of my invention it is to be understood that within the scope of my invention wide deviations 20 may be made therefrom without departing from the spirit of my invention.

Claims.

1. A drilling machine having in combination, a cradle, supporting means in which 25 said cradle is slidingly mounted, means for feeding the cradle relatively to said supporting means, a percussive hammer tool, said tool having a reduced rearward end, lugs projecting from opposite sides of said 30 reduced rearward end, said cradle having lugs at opposite sides thereof embracing said reduced rearward end of said percussive hammer tool and against which said lugs projecting from opposite sides of said reduced rearward end bear, releasable means 35 for engaging the rearward end of said percussive hammer tool and forcing the same forwardly to clamp it against said lugs projecting from said cradle, said percussive 40 hammer tool having side bolts, means forming forwardly facing shoulders at the forward portion of said percussive hammer tool, a member carried by said side bolts and clamped thereby against said shoulders, 45 means carried by said member and cradle for detachably locking the two together, said lugs projecting from said reduced rearward end of said tool having means for attaching a handle to said tool.

50 2. A drilling machine having in combination, a cradle, a percussive tool, means for detachably fastening the forward end portion of said tool to said cradle, said tool having at its rearward end a reduced portion 55 with laterally projecting lugs, lugs carried by said cradle and embracing said reduced portion forwardly of said laterally projecting lugs, and means engaging the rearward end of said tool for forcing said laterally 60 projecting lugs against said lugs carried by said cradle.

65 3. A drilling machine having in combination, a cradle, a percussive tool, cooperating means carried by said cradle and said percussive tool for locking the two together and

holding them so locked when said tool is forced forward relative to said cradle, and means carried by said cradle and movable longitudinally thereof for engaging said tool and forcing it forward relative to said cradle. 70

4. A drilling machine having in combination, a cradle, a percussive tool carried by said cradle, cooperating means carried by said cradle and tool for locking the forward portion of said tool to said cradle by forward motion of said tool relative to said cradle, a pair of jaws carried by said cradle, and means for moving one of said jaws forward toward the other jaw for clamping the rearward portion of said tool between said 75 jaws and for holding said cooperating means in operative relation.

5. A drilling machine having in combination, a cradle, a percussive tool carried by said cradle, said tool having side rods, an adapter carried by said side rods for securing the forward portion of said tool to said cradle, a vise carried by the rearward end of said cradle, said vise having its movable jaw arranged to slide longitudinally of said cradle for clamping the rearward portion of said tool between said jaws. 80

6. A drilling machine having in combination, a cradle, a percussive tool, means forming a socket at the forward end portion of said cradle for receiving a forwardly directed lug carried by said tool, an upstanding jaw at the rearward end of said cradle against which a forwardly facing surface of said tool rests when said forwardly directed lug is inserted into said socket, a movable jaw carried by the rearward end portion of said cradle for engaging a rearwardly facing surface of said tool and means for forcing said last named jaw forwardly against said rearwardly facing surface. 95

7. A drilling machine having in combination a cradle, a percussive tool, means forming a socket at the forward end portion of said cradle for receiving a forwardly directed lug carried by said tool, an upstanding jaw at the rearward end of said cradle against which a forwardly facing surface of said tool rests when said forwardly directed lug is inserted into said socket, a movable jaw carried by the rearward end portion of said cradle for engaging a rearwardly facing surface of said tool, and a screw threaded into a nut carried by said cradle for forcing said last named jaw forwardly against said rearwardly facing surface. 100

8. A drilling machine having in combination, a cradle, a percussive tool, means forming a socket at the forward end portion of said cradle for receiving a forwardly directed lug carried by said tool, an upstanding jaw at the rearward end of said cradle against which a forwardly facing surface of said tool rests when said forwardly directed lug is inserted into said socket, a second 110

jaw, a screw having a universal connection with said second jaw, said second jaw when said screw is operated being forced against a rearwardly facing surface of said tool for 5 clamping said tool between said jaws.

9. A drilling machine having, in combination, a cradle, a percussive tool, means comprising relatively movable jaws for clamping the rearward end of said tool to said 10 cradle and rigidly holding said tool against forward and rearward movement relatively to said cradle, and a lug and socket connection between the forward end of said tool and cradle comprising male and female parts 15 engageable and disengageable by relative movement between said tool and cradle.

10. A drilling machine having in combination a cradle, a percussive tool, means for clamping the rearward end of said tool to 20 said cradle, a plate detachably carried by the forward end of said tool, said plate having a forwardly directed lug, and means carried by said cradle forming a socket for receiving said lug.

25 11. A drilling machine having in combination a cradle, a percussive tool, means comprising relatively movable jaws for rigidly clamping the rearward end of said tool to said cradle, a plate rigidly and detachably carried by the forward end of said tool, and means for connecting said plate and cradle by movement of said tool longitudinally of said cradle.

12. A drilling machine having in combination a cradle, a percussive tool, means comprising relatively movable jaws for clamping the rearward end of said tool to said cradle, said tool having a pair of side rods, a member clamped to said tool by said 40 side rods and having openings through which said rods pass, and a detachable connection between said member and said cradle.

13. A drilling machine having in combination a cradle, a percussive tool, means comprising relatively movable jaws for clamping the rearward end of said tool to said cradle, said tool having side rods, a U-shaped member having perforations receiving 50 said rods, the latter clamping said member rigidly in assembled relation with said tool, and said member and cradle having cooperating portions designed to prevent relative rotation between the two for locking them together.

14. A drilling machine having in combination a cradle, a percussive hammering tool, means for securing the forward end of said tool to said cradle, a clamp carried 55 by said cradle for clamping the rearward end of said tool to said cradle, a manually operated rotary member for actuating said clamp and yielding means for preventing turning of said rotary member and conse-

quent loosening of said clamp under the influence of vibration of said machine. 65

15. A drilling machine having in combination a cradle, a percussive hammering tool, means for securing the forward end of said tool to said cradle, a rotary member 70 operating a clamp carried by said cradle for clamping the rearward end of said tool to said cradle, and a compression spring carried by said rotary member and cooperating therewith and with a stationary part 75 carried by said cradle for preventing loosening of said clamp under the influence of vibration of said machine.

16. In a drilling machine, a cradle having spaced guide bars, a cradle support having ways in which the guide bars of said cradle are slidably mounted, a feed screw having a thrust bearing carried by said cradle support, a nut carried by said cradle, and said nut having flattened sides located 80 between and bearing against said guide bars, whereby rotation of said nut relatively to said cradle is prevented.

17. A drilling machine having in combination, a percussive tool, a cradle for said tool, cooperating means on said cradle and tool for securing one to the other comprising a vise on said cradle with jaws movable relatively to each other longitudinally of said cradle, and handle attaching members 90 on opposite sides of said percussive tool and transversely disposed thereto for engagement with said vise. 95

18. A drilling machine having in combination, a percussive tool, a cradle for said tool, cooperating means carried by said tool and cradle for locking one to the other by relative longitudinal movement, and a vise carried by said cradle for rigidly clamping said tool to the cradle, said vise having a 100 jaw movable longitudinally of said cradle. 105

19. A drilling machine having in combination, a cradle, a percussive tool carried by said cradle, said tool having the reduced portion 11 and lugs 15, and a vise carried 110 by said cradle for gripping said lugs, said vise having cooperating jaws one of which is provided with the portions 53 engaging said lugs.

20. A drilling machine having in combination, a cradle, a percussive tool carried by said cradle, an adapter 29 carried by said tool, an ear on said cradle, said adapter and ear having the cooperating slot 51 and lug 31, and clamping means comprising a forward stationary jaw and a rearward movable jaw carried by said cradle and engaging 115 said tool for securing it rigidly to said cradle. 120

In testimony whereof, I have signed my 125 name to this specification.

GEORGE H. GILMAN.
